LLP**(57) CLAIM**

The ornamental design for a snow plow headlamp, as shown
and described.

DESCRIPTION

FIG. 1 is a top front right perspective view of my new,
original and ornamental design for a snow plow headlamp.
FIG. 2 is a front view thereof.

FIG. 3 is a left side view thereof.

FIG. 4 is a right side view thereof.

FIG. 5 is a top view thereof; and,

FIG. 6 is a bottom view thereof.

The broken lines illustrate environment and/or unclaimed
boundaries and/or unclaimed features, are for illustrative
purposes only, and form no part of the claimed design.
